(57) **CLAIM**

The ornamental design for a walking aid accessible modular
stair assembly as shown and described.

DESCRIPTION

FIG. 1 is a front perspective view of a first embodiment of
a walking aid accessible modular stair assembly;
FIG. 2 is a front view thereof;
FIG. 3 is a rear view thereof;
FIG. 4 is a left side view of thereof;
FIG. 5 is a right side view thereof;
FIG. 6 is a top view thereof;
FIG. 7 is a bottom view thereof;
FIG. 8 is an enlarged and partial view of the front perspective
view of FIG. 1 from a different viewpoint;
FIG. 9 is an enlarged and partial view of the front perspective
view of FIG. 1 from a different viewpoint;
FIG. 10 an enlarged and partial view of the front perspective
view of FIG. 1 from a different viewpoint;
FIG. 11 is an enlarged and partial view of the front perspective
view of FIG. 1 from a different viewpoint;
FIG. 12 is an enlarged and partial view of the front perspective
view of FIG. 1 from a different viewpoint.
FIG. 13 is a front perspective view of a second embodiment
of a walking aid accessible modular stair assembly;
FIG. 14 is a front view thereof;
FIG. 15 is a rear view thereof;
FIG. 16 is a left side view of thereof;
FIG. 17 is a right side view thereof;
FIG. 18 is a top view thereof;
FIG. 19 is a bottom view thereof; and,
FIG. 20 is a perspective view of the walking aid accessible
modular stair assembly of FIG. 1 shown in an exemplary
environment which is illustrated in broken lines.
The broken lines in FIGS. 8-12 illustrate breakaway lines.
The appearance of any portion of the walking aid accessible
modular stair assembly between the break lines shown in
FIGS. 13-19 form no part of the claimed design.

(Continued)

The broken lines in FIG. 20 illustrate environmental structure that forms no part of the claimed design.
